UNITED STATES PATENT OFFICE

125,658

DESIGN FOR A CLOCK

Jerome De Haes, Chicago, Ill., assignor of one-half to Albert S. Malecki, Chicago, Ill.

Application December 26, 1940, Serial No. 97,616

Term of patent 14 years

To all whom it may concern:

Be it known that I, Jerome De Haes, a citizen of the United States, residing at Chicago, in the county of Cook and State of Illinois, have invented a new, original, and ornamental Design for a Clock, of which the following is a specification, reference being had to the accompanying drawing, forming a part thereof, and in which

Fig. 1 is a face view of a clock showing my new design; and

Fig. 2 a top plan view of the same.

I claim:

The ornamental design for a clock, as shown.

JEROME DE HAES.
